UNITED STATES PATENT OFFICE.

URI D. FOSTER AND JOHN LITKE, OF HARTFORD, CONNECTICUT, ASSIGNEES TO THE HART & HEGEMAN MANUFACTURING COMPANY, OF HARTFORD, CONNECTICUT, A CORPORATION OF CONNECTICUT.

FEEDER FOR METAL-WORKING MACHINES.

1,350,715.

Specification of Letters Patent. Patented Aug. 24, 1920.

Application filed March 17, 1919. Serial No. 283,120.

To all whom it may concern:

Be it known that we, URI D. FOSTER and JOHN LITKE, citizens of the United States, residing at Hartford, in the county of Hartford and State of Connecticut, have invented certain new and useful Improvements in Feeders for Metal-Working Machines, of which the following is a specification.

This invention relates to what we shall for convenience term a feeder for metal-working machines. It is conceivable of course that the invention can be incorporated in machines of other kinds for which reason we have as will be clear, selected the title given for the purpose stated. We have found in practice the invention to be particularly advantageous when used in connection with a screw-thread forming machine. We might say that our primary motive is the provision of efficient and durable means for effecting the proper presentation of an article to a device which is to operate on it. When the invention is incorporated in a screw-thread forming machine, the function of the feeding mechanism is to assure the proper presentation of a blank to threading means which may be and in this case, preferably is, in the form of dies. We might observe that in existing types of screw-thread-rolling machines with which we are familiar, considerable difficulty attends the proper presentation of the blanks to the rolling means.

In the drawings accompanying and forming part of the present specification we have illustrated in detail a form of embodiment of the invention which we will set forth fully in the following description to enable those skilled in the art to practice the invention. Obviously we are not restricted to this disclosure; we may depart therefrom in several respects within the scope of the claims following said description.

Referring to said drawings:

Figure 1 is a sectional side elevation of a feeder involving the invention as incorporated in a thread rolling machine.

Fig. 2 is a sectional top plan view and Fig. 3 is a sectional front elevation of the same.

Fig. 4 is a section on the line 4-4 of Fig. 1 looking in the direction of the arrows.

Fig. 5 is a side elevation, Fig. 6 an elevation as seen from the right in Fig. 5

and Fig. 7 a bottom plan view of a feeder- 55 element.

Fig. 8 is a sectional detail view of a modification.

Figs. 9, 10 and 11 are diagrammatic plan views of the die members and certain coöperative parts showing the course of a blank. 60

Like characters refer to like parts throughout the several views.

As we have already indicated the feeding mechanism is susceptible of general use. In action, however, it has demonstrated its particular usefulness in the metal-working art, having been employed in conjunction with thread-forming machines and particularly of that character used for rolling a thread. 70 We have in fact shown certain of the parts of a thread-rolling machine and these to illustrate the advantages of the structure. The machine includes in its structure a chute or runway as 2 consisting as shown of complementary or duplicate plates or walls spaced apart a distance equaling practically the diameter of the shanks of the blanks which traverse said chute or runway, the heads of the blanks as 3 traveling along the upper inclined portion of the chute or runway in their passage toward the thread-rolling mechanism. 75

The thread-rolling mechanism comprises a fixed die member as 4 and a reciprocating die member as 5 through the joint action of which, on the reciprocation of the die member 5 the thread is formed. One of the difficulties heretofore has been the proper presentation of the blanks to these die members. The structure which we provide insures the accurate supply of blanks to the die mechanism. It will be understood that the chute or runway and die members are not new with us. Above the chute or runway 90 2 is a guard rail 6 which extends virtually to the lower end of the chute and is inclined as is common.

In addition to a chute or runway as 2 or equivalent element, we provide what we term a "carrier-member" such as that denoted in a general way by 7. This carrier-member is practically as shown in the form of a blade and is united to a support as 11 which is mounted in the present case for 100 rocking movement. The carrier-member comprises a somewhat elongated shank as 9 the upper portion of which as illustrated, is

at somewhat a steep angle and the lower portion of which is practically perpendicular. From the lower end of the perpendicular portion of the shank 9 there extends laterally the foot or base piece 10 which functions as we will hereinafter explain. The upper angular portion of the shank 9, of the carrier member 7 as shown is rigidly fastened to the lower portion of the apron 11, supported as by the pivot 12 above the upper angular branch of the bracket 13, the lower horizontal branch of which is adjustably connected as by a screw 14 extending through an elongated slot in said branch and threaded into the block 15 constituting a fixed part of the frame 16 of the machine. By loosening the screw 14 the block 13 may be adjusted to correspondingly adjust the carrier member 7 toward or from the chute 2 or runway 2. When the adjustment is accomplished the screw 14 is set. The carrier member 7 is normally held in operative relation as by the spring 17 set in mating bores or cavities in the upper angular portion of the block 13 and apron 11.

The carrier member or rather the vertical portion of the shank 9 thereof terminates at its lower end as we have noted in a foot 10, the inner side of which is rounded or convex, the upper surface of said foot being beveled. The inner portion of this foot engages under the head of a blank 3 just as the same emerges from the chute or runway 2. It will of course be understood that the function of the spring 17 is to normally hold the foot in its said operative position under the head of the advance screw blank as shown clearly in Fig. 3. As a matter of fact as the advance blank leaves the chute the head of said blank is at once caught by the foot 10. It will of course be understood that the foot 10 catches the extreme forward blank just as it leaves the feed chute 2 and holds said blank in position for feeding to the die mechanism. The consequence of this is that the shank of the blank is thus by the foot, tipped forwardly so that it will not catch the chute or runway 2 when advanced toward the die mechanism.

The carrier member 7 as we have already explained supports the blank by engaging under the head thereof in its passage from the chute or runway 2 toward the thread rolling mechanism. It is fed across the gap in front of the chute and toward the die mechanism in a positive manner for instance as by means including a main feeder member 19 which has a reciprocation and which is generally power driven. This feeder member 19 actually forces the advance blank from the chute or runway.

Said feeder member 19 has on the under side thereof the downwardly extending bead 20 practically midway between the ends 65 thereof, and it also has on its outer or front

side a longitudinal channel or rabbet 21 to receive for sliding movement, the secondary feeder member 22 the latter functioning to push the blank received from the primary feeder member 19 into the space between the dies 4 and 5. The primary feeder member 19 has on its under side at the front, a transverse recess or aperture 23 the inner side or wall of which is the front end of the bead 20. The walls of the recess or aperture 23 diverge forwardly or away from the chute 2 and said recess is shallower at the back than at the front. Normally the foot 10 is situated in this recess. As a screw leaves the chute or runway 2 it enters the recess 23 and its head is caught by the foot 10 in the manner previously described. The primary feeder member having an advance movement toward the right for instance in Fig. 1, it is evident that the front face of the bead 20 will push the screw blank sidewise on said advance to get the head of the blank entirely out of the recess 23. The back or rear side wall of the recess is really the front end of the bead 20. When the head of the screw is entirely out of the recess, it being still supported by the foot 10, it will be engaged by the secondary feed member 22 on its advance toward the right in Fig. 1 so that it can be pushed into the space between the die members 4 and 5 and there rolled to form a screw.

Fig. 8 shows a modification. In this case the primary feeder member 25 is practically like the corresponding feeder member 19 already described. The die mechanism we will denote in a general way by 26. The secondary feeder member 27 in action is like the secondary feeder member 22 already described. The secondary feeder member 27, however, has in its upper forward corner a notch 28 in which the head of the blank 29 may be received. In view of this condition the blank is positively held against longitudinal movement in its feed toward the die mechanism 26, being shown by dotted lines as occupying a position between the dies which are like those already described.

In the structure shown for instance by Figs. 1, 2 and 3 the carrier member 7 is supported for swinging movement back of its operative end or that part which is provided with the foot 10. This mounting provides that when the foot portion of said carrier member is moved outward or to the left for illustration in Fig. 3, the foot will be operated or practically raised so as to lift the head of the blank supported thereby against the overhanging portion of the primary feeder member 19.

What we claim is:

1. The combination of a chute to receive articles in the form of headed shanks, the chute supporting the heads of the articles for feed therealong, means for positively 130

swinging forward away from the chute the lower portion of the advance article emerging therefrom, and means for imparting a movement to the article in a direction 5 transverse to its line of movement along the chute.

2. The combination of a chute to receive articles in the form of headed shanks, the chute supporting the heads of the articles 10 for feed therealong, means for positively tipping forward away from the chute the lower portion of the advance article emerging therefrom, die mechanism, and means for imparting a movement to the article in 15 a direction transverse to its line of movement along the chute and into the die mechanism.

3. The combination of a chute to receive articles in the form of headed shanks, the chute supporting the heads of the articles 20 for feed therealong, means to engage an article as it emerges from the chute and for moving its shank away from the chute, means to prevent upward movement of the headed shank practically as it leaves the 25 chute, and means for moving the article away from the chute.

4. The combination of a chute to receive articles in the form of headed shanks, the chute supporting the heads of the articles 30 for feed therealong, means to engage and support the head of an article as it emerges from the chute and for moving its shank away from the chute, while its head is thus supported, and independent means for moving the article in a direction transverse to its line of movement along the chute.

5. The combination of a chute to receive articles in the form of headed shanks, the chute supporting the heads of the articles 40 for feed therealong, means to engage the head of an article as it emerges from the chute and for tipping its shank away from the chute, a reciprocatory feeder having means to engage the head of the article practically as it leaves the chute, and for moving the article free of the chute, and a second reciprocatory feeder to engage the article when freed by the first feeder and to move it in a direction transverse to its direction of travel along the chute.

6. The combination of a chute to receive articles in the form of headed shanks, the chute supporting the heads of the articles

for feed therealong, and a movably mounted part provided with means to engage under 55 the head of an article as it emerges from the chute and to tip the shank of the article away from the chute.

7. The combination of a chute to receive articles in the form of headed shanks, the 60 chute supporting the heads of the articles for feed therealong, and a swinging part provided with means to engage under the head of an article as it emerges from the chute to cause the shank of the article to 65 swing away from the chute.

8. The combination of a chute to receive articles in the form of headed shanks, the chute supporting the heads of the articles for feed therealong, and a swinging spring- 70 actuated part to engage under the head of an article as it emerges from the chute and to cause the shank of the article to tip away from the chute.

9. The combination of a chute to receive 75 articles in the form of headed shanks, the chute supporting the heads of the articles for feed therealong, a movably-mounted part provided with means to engage under the head of an article as it emerges from 80 the chute and to tip the shank of the article away from the chute, and means to free the article from the chute.

10. The combination of a chute to receive articles in the form of headed shanks, a 85 chute supporting the heads of the articles for feed therealong, a spring-actuated part to engage under the head of an article as it emerges from the chute and to cause the shank of the article to tip away from the 90 chute, a reciprocatory feeder adapted on its advance to move the article wholly free of the chute and of said feeder and also to engage its head and to prevent upward movement of the article, and a second reciprocatory feeder adapted on its advance to 95 engage the article and to move the same in a direction transverse to its line of motion along the chute.

In testimony whereof we affix our signatures in the presence of two witnesses.
